UNITED STATES PATENT OFFICE.

LAZARD KAHN, OF HAMILTON, OHIO, ASSIGNOR TO F. & L. KAHN & BROS.,
OF SAME PLACE.

DESIGN FOR A STOVE-BASE.

SPECIFICATION forming part of Design No. 25,108, dated January 28, 1896.

Application filed December 30, 1895. Serial No. 578,830. Term of patent 14 years.

To all whom it may concern:

Be it known that I, LAZARD KAHN, a citizen of the United States, residing at Hamilton, Butler county, Ohio, have invented and produced a new and original Design for Stove-Bases, of which the following is a specification, reference being had to the accompanying drawing, showing the same in perspective.

The leading feature of my design consists on a stove-base having a doorway in one of its walls and having projecting outwardly from another of its vertical walls a circular register, from the center of which projects a handle.

A is the base proper. B is the doorway in one of its vertical walls. C is the circular register projecting outwardly from one of the other vertical walls. D is the handle projecting outwardly from the center of the circular register.

What I claim is—

The design for a stove-base, as herein shown and described.

LAZARD KAHN.
